UNITED STATES PATENT OFFICE

CESARE C. CAMPUS, OF SANTA MONICA, CALIFORNIA

CONCEALED HINGE TOILET SEAT

Application filed October 24, 1931. Serial No. 570,888.

This invention relates to an improvement in toilet seats for the purpose of lowering their cost, improve their quality, facilitate the cleaning of the bowl, obtaining the advantage of covering the hinge fixture with celluloid, a neater appearance and stronger construction.

In accordance with the common practice, toilet seats are of different shapes and materials, some are equipped with a lid; this type is best adapted to homes; some are without lid, which are mostly in use in schools, hotels, office and public buildings, but all these types are equipped with metal hinges which are always exposed to view; it is therefore necessary to cover them always with some finish so as to give them a neat appearance. In some cases they are finished in Duco and in others with vulcanized rubber, but the majority of all the different types today in use, are either nickel or chromium plated.

Some types of hinges are provided with an offset, but all types of toilet seats equipped with said hinge fixtures as customarily constructed and used, have several disadvantages, namely:

The Duco finish is a long and expensive process, and which with use discolors and chips easily.

The vulcanizing process is also a long and expensive one, and the choice of color is limited to black. This prevents the hinges matching whatever color the seat is covered with.

The nickel and chromium finishes become oxidized for obvious reasons, therefore it is necessary to polish them daily, and this plating process is also expensive.

In hotels, where hundreds, and in some cases thousands of toilet seats are installed the upkeep is very expensive, considering the polishing material and labor entailed.

The hinges without an offset have the inconvenience of bringing the seat, whether in a raised or a lowered position, very close to the bowl, thus rendering the cleaning of the rear top thereof, difficult.

None of the types of hinges at present in use, can be covered with celluloid like the

seat, and can therefore not match the color thereof.

The object of my invention is to overcome all the above described inconveniences in the following manner:

The various inconveniences of the different kinds of finishes for the hinges are eliminated, by eliminating the cause, namely by hiding all the metal parts of which they are composed and which at present are exposed.

The inconvenience to clean the rear top of the flange of the bowl, when hinges without an offset are used, is eliminated, because said described spot is freed of all obstruction; this is obtained by cutting from the seat that portion of material which prevents easy cleaning, but leaving sufficient material at the rear end of said seat, so as to form two suitable extensions to receive the hinge fixture combination pivotally mounted thereto, and said extensions longitudinally located beyond the width of the flange in question, thus leaving the flange of the bowl clear all over.

The inconvenience of limited choice of color and material to cover the hinge fixture is eliminated, as the member hiding the metal parts, which also cooperates to form the hinge fixture, is so constructed that it can be of suitable material to overcome the difficulty of covering such piece with celluloid sheeting. This piece can be of hardwood, same as the seat, or of any other suitable material, and in view of its shape and construction it can, obviously, be covered to match the material and color of the seat.

The cost is lowered because the number of metal parts is less, and those left do not need to be finished.

The quality is improved by the special construction of the hinge bar which replaces the ordinary hinge fixture.

The entire construction is very substantial, eliminating the possibility of the hinges breaking, and the general lines are so neat that the cheap appearance of inexpensive seats is eliminated.

The foregoing objects and advantages, together with my subsequent features, which may be developed in the description, may be

best appreciated from a description read in conjunction with the drawings, in which:

Fig. 1 is a plain view of a toilet seat partly in section showing a form of my invention 5 embodied therein;

Fig. 2 is a view on line 3—3 of Fig. 1;

Fig. 3 is a view on line 7—7 of Fig. 1;

Fig. 4 is an enlargement view in section, 10 of the bushings shown in Figs. 1 and 3;

Fig. 5 is a front view of the escutcheon carried by Fig. 4;

Fig. 6 shows another form of the escutcheon for bushings in Fig. 4.

Fig. 7 is a front view of the angular escutcheon.

Fig. 8 is a plain view, partly in section, of another form of my invention;

Fig. 9 is a view on line 6—6;

Fig. 10 is another view on line 5—5;

Fig. 11 is an elevation side view of another form of my invention;

Fig. 12 is a backview partly in section on line 4—4 of Fig. 11 carrying a fragment of seat 9 mounted thereto.

In all the forms embodying my invention, 20 the principal elements consist of a toilet seat, provided at the rear end thereof with two extensions, a cross bar acting also as an escutcheon, by concealing all of the metal parts and concurring to form the hinge fixture with said cross bar. Said cross bar can also be formed in one piece with the toilet bowl, thus eliminating the two studs, which, 25 in combination with the pivots form the hinge posts to attach the seat to the bowl.

Referring to the drawings, and particularly to Figs. 2, 3, 8, 9, 10, 11 and 12 a fragment of a toilet bowl is indicated at 18.

Fig. 1 represents a plain view of seat 9, 40 provided at the rear end with extensions 10, carrying bushings 11, held in position by screw 12. The concealing member 13 in co-operation with pivots 14, studs 15 screwed thereto, for the hinge fixture fastened to flange 16 of bowl 18 by nuts 19 carrying a metal washer 20, a rubber washer 21 and rubber packing 32, to act as cushion, as shown in Figs. 2, 3, 9 and 10. Member 13 is provided with cavity 22 to put in position 45 pivots 14 carrying hole 23 for the purpose of inserting a suitable tool to facilitate their removal in case of need; said pivots are horizontally mounted in a suitable bore 24. The concealing member 13 is covered with celluloid material 25, same color and material as seat 9; it is understood that it can be covered with different color and material, if desired.

The bushing 11, as shown in Fig. 4, is provided with a perforation 28 for receiving the 60 screw 12 which serves to hold the bushing securely within the recess formed in one of the extensions on the seat. With the bushings in place the celluloid escutcheon 27 is securely held on the exposed flange of the same. In Fig. 6 a modified construction of

bushing is disclosed wherein the escutcheon comprises a ring 29, the same being securely mounted on the flange portion of the bushing.

In Figs. 8, 9 and 10 there is disclosed a modified construction of seat 9, the same 70 having extensions 10 and being hinged in a manner similar to the preferred construction above described. This type of seat is open at the front and is mostly used in hotels, schools, public buildings and offices and while 75 not usually finished in celluloid can be so finished if desired. The concealing bar 13 carries pivots 14 provided with apertures 23 and studs 15. In this modification the bushings are not flanged since this is not necessary when the seat is not covered with material which can become detached by dampness or contact with water.

In the constructions described the seat is rigidly attached to the rear flange of the bowl, provision, however, being made to permit hinging of the seat with respect thereto. A feature of the invention is the concealing of all metal parts, the particular arrangement in addition permitting ready detachment of the same from the bowl when desired. The concealing bar having the cavity 22 may be constructed of metal or of wood and finished so as to correspond with the finish of the seat, the cavity and the arrangement of the pivots 14 permitting easy access to the hinge members for repair purposes. Also an important feature is the threaded 85 securing which the pivots 14 have with the studs 15, the construction being relatively simple but serving to securely hold the pivot members and the concealing bar in place.

In Figs. 11 and 12 the concealing member is formed integral with the bowl 18, and as shown the same is formed with a cavity 22 for receiving the inwardly projecting ends of the pivots 14, the latter being mounted in the tubular members 30 of suitable plastic material, preferably lead, to take care of any possible imperfection in the bore 24 provided in the concealing member. Extensions 31 of the pivots are flat and are bent, after which the cavity is filled with any kind of suitable hardening material whereby the studs are prevented from turning.

Although I have shown several forms of my invention, I am aware that, to those skilled in the art, other forms will readily suggest themselves. It is, therefore, my intention to include all such forms and modifications in the nature of refinements of my invention that come within the scope of the specification and the essence of the invention, as expressed in the appended claims.

I claim as my invention:

1. A seat provided at its rear end with a pair of spaced hinge projections having aligned hinge sockets in their inner faces, and stationary hinge means having oppositely projecting pintles extending into the sockets

125

130

of the hinge projections on the seat, each of said seat projections lying close to the stationary hinge means and each hinge pintle being concealed within the stationary hinge means and the seat projections.

2. A seat provided at its rear end with a pair of spaced hinge projections having aligned hinge sockets in their inner faces, a stationary hinge member located between the hinge projections and provided with aligned passages open at opposite ends and aligned with the hinge sockets of the seat projections, hinge pintles adjustable endwise within the passages and projecting into the sockets of the respective hinge projections, and means for securing the fixed hinge member to a bowl including studs, the stationary hinge member having bottom openings communicating with its passages, and the pintles having screw threaded openings to receive the screw threaded upper ends of the studs.

3. A seat provided at its rear end with a pair of spaced hinge projections having aligned hinge sockets in their inner faces, a stationary hinge member located between the hinge projections and provided with means for securing the hinge member to a bowl, and a pair of hinge pintles carried within the hinge member and adjustable outwardly through the ends thereof and into the hinge sockets of the respective projections on the seat, said hinge member having an opening exposing the pintles for convenience in adjusting the latter.

4. The combination with a bowl, of a fixed hinge member rising from the bowl, a seat provided at its rear end with spaced hinge projections embracing the stationary hinge member, said hinge projections being provided in their inner faces with aligned hinge sockets, and pintles mounted within the stationary hinge member and movable outwardly through the ends of said member into the respective sockets of the seat.

5. The combination of a bowl having an integral hinge member rising therefrom and provided in opposite ends with aligned open-ended pintle-receiving passages, a seat having spaced rearwardly directed hinge projections extending across and adjacent the opposite ends of the stationary hinge member and provided in their inner faces with hinge sockets in alignment with the passages of the fixed hinge member, and hinge pintles extending through the passages with their outer ends lying in the hinge sockets of the seat projections and their inner ends projecting through the inner ends of the passages, the stationary hinge member having a recess into which the inner ends of the hinge pintles project and capable of receiving means for holding the hinge pintles in place.

6. The combination with a bowl, of a seat having a pair of transversely spaced hinge projections extending rearwardly therefrom

and provided in their inner faces with hinge sockets closed at their inner ends, hinge pintles lying in the respective sockets and projecting through the open ends thereof, and pintle-mounting means fixed upon the bowl and lying between the hinge projections and extending the full distance from one projection to the other, the portions of the pintles extending from the seat projections being mounted in the said pintle mounting, the seat projections and the pintle-mounting housing and concealing the pintles.

7. A seat having a pair of transversely spaced hinge projections extending rearwardly therefrom and provided in their inner faces with hinge sockets closed at their inner ends, hinge pintles lying in the respective sockets and projecting through the open ends thereof, and pintle-mounting means lying between the hinge projections and extending the full distance from one projection to the other, the portions of the pintles extending from the seat projections being mounted in the said pintle-mounting, the seat projections and the pintle-mounting housing and concealing the pintles, and means for securing the pintle-mounting to a bowl.

8. The combination with a bowl having a seat-mounting flange, of a seat having rearwardly extending hinge projections spaced to swing past the ends of the flange when raising and lowering the seat, a pintle-mounting on the flange, and pintles carried by the mounting and projecting in opposite directions therefrom, the hinge projections of the seat having sockets in their inner faces, and the hinge pintles extending into their respective sockets and concealed by the mounting and the seat projections.

9. A seat provided at its rear end with a pair of spaced hinge projections having aligned hinge sockets in their inner faces, a stationary hinge member located between the hinge projections and provided with aligned passages open at opposite ends and aligned with the hinge sockets of the seat projections, hinge pintles positioned within the passages and projecting into the sockets of the respective hinge projections, and means for securing the stationary hinge member to a bowl, said stationary hinge member having a bottom opening communicating with its passages, and the pintles having screw threaded openings for receiving the screw threaded upper ends of the securing means.

10. A seat provided at its rear end with a pair of spaced hinge projections having aligned hinge sockets in their inner faces, a stationary hinge member located between the hinge projections and having means securing the member to a bowl, and a pair of hinge pintles carried within the hinge member and projecting from the respective ends thereof and into the hinge socket

of the adjacent seat projection, the said hinge pintles being held in position in the stationary member by the securing means therefor.

5 In testimony whereof, I have hereunto set my hand at Santa Monica, California, this 19th day of October, 1931.
